E. F. CHAFFEE

COMBINED SASH HOLDER AND STARTER

Filed Feb. 3, 1927

UNITED STATES PATENT OFFICE.

EDWARD F. CHAFFEE, OF SYRACUSE, NEW YORK, ASSIGNOR TO THE O. M. EDWARDS COMPANY INC., OF SYRACUSE, NEW YORK, A CORPORATION OF NEW YORK.

COMBINED SASH HOLDER AND STARTER.

Application filed February 3, 1927. Serial No. 165,513.

This invention relates to combined window sash locks or holders and starters, where the starter member prys against the sill during the operation of the sash holding mechanism to withdraw the locking bolt or member thereof and it has for its object, particularly simple and efficient mechanism by which the sash starter member is member is moved out of effective position at the 10 end of the operation of the sash holding mechanism, that is, when the bolt or other locking member is entirely withdrawn so that during the lowering of the sash, the sash starting member will be out of operative position and not engage the sill so that the window can be entirely closed as the sash starter is entirely out of operation until the operator again releases the sash holding mechanism, which he does only when the 20 sash is closed, and it further has for its object, means whereby the sash starter member can return to operative position in order to be ready to act to pry upon the sash after the sash has been once closed.

25 The invention consists in the novel features and in the combinations and constructions hereinafter set forth and claimed.

In describing this invention, reference is had to the accompanying drawings in which 30 like characters represent corresponding parts in all the views.

Figures 1 and 2 are elevations of slightly different forms embodying my invention.

Figure 3 is an inner face view partly 35 broken away, of the sash lock shown in Figure 1.

Figure 4 is an inner face view of the sash lock shown in Figure 2.

Figure 5 is an enlarged sectional view on 40 line 5—5, Figure 3.

This sash starter and holder comprising generally mechanism including a manually operable element, a downwardly movable sash starting thrust member arranged in the 45 path of the operating element to be effectively actuated thereby during the initial movement of the operating element, and means by which the starting member is relieved of effective thrust received from the manually operable element, as the operating element 50 approaches the end of its throw by shifting one or the other of said parts. It further preferably comprises means for automatically returning the thrust member into effective thrusting relation during the return move-

ment of the operating element to its starting position, the thrust member being preferably shiftable laterally relatively to its endwise movement during the retrograde or return movement of the operating member to 60 its starting position by cam means, which return it into effective thrusting relation.

In the illustrated embodiment of my invention in which this sash starter mechanism is combined with one old form of sash holding mechanism or sash lock, the sash starting or thrust member is shiftable relatively to the operating element out of effective thrusting position as well as back into thrusting position, and is connected to the 65 operating element or lever of the sash holder mechanism and moves therewith, and is normally in position to thrust against an abutment usually provided on the sill. It is shiftable relatively to the operating element or lever out of effective thrusting relation by being shifted by cam means out of alignment with the abutment as the operating element approaches the end of its throw, and is also shifted back into effective thrusting relation by cam means during the return of the operating element to its normal 70 or starting position. However, I, do not limit my invention to shifting the thrust member at an angle to its thrusting movement out of effective thrusting relation by moving it out of alignment with the abutment, as it may remain in alignment with the abutment, and operate into and out of effective relation with the operating element 75 without departing from the spirit of my invention. In other words more or less change 80 may be made in the construction hereinafter described without departing from the spirit 85 of my invention.

More specifically the illustrated embodiment of this sash starter and holder comprises generally sash holding mechanism including an operating element, a sash starter member movable against an abutment on the 90 sill when the sash is closed, the sash starter member being connected to the operating element to be moved thereby and being normally aligned with the abutment and shiftable laterally at the end of the operating or 95 withdrawal operation of the sash holding mechanism, and means for shifting said sash starter member laterally out of alignment with the abutment at the end of the operating movement and for again moving it into 100 alignment with the abutment at the end of the 105 operating movement.

alinement with the abutment when the sash holding mechanism is released. The sash starter may be combined with any well known form of sash holder or sash holding mechanism, and is here shown as combined with a sash lock of the type shown in my Patent No. 1,567,571, dated December 29, 1925, although it may be combined with any other form of sash holder or lock.

10 Sash holder mechanisms are usually not mounted directly upon the sash but are unitary structures and comprise a base, which is mounted on the sash and this base is usually in the form of a housing or casing.

15 1 designates the base, it being shown as in the form of a casing or a block formed with a recess 2 opening through its rear face or its face opposed to the sash, the base 1 being secured to the sash in any suitable manner as by screws 3.

20 The sash holding mechanism is spring pressed. That is, it is pressed into locking position by a spring, the sash holding mechanism here shown includes a sliding locking bolt 4 suitably guided in the base or casing

25 1 and having teeth 5 projecting out of the recess 2 in position to engage a rack or similar device 6 on the window frame 7. The sash holding mechanism also includes an operating element, it being here shown as a lever 8 pivoted within the casing at 9, and having an arm 10 coacting with the bolt to withdraw it against a spring 11 when the lever 8 is actuated, this arm 8 also serving to

30 return the lever to its normal position under the influence of the spring 11. The lever 8 is here shown as a hand lever, it having a finger engaging portion 12 extending outside of the housing 1 and arranged in juxtaposition to a grip or pinch handle 13 rigid with

35 the casing 1. The construction thus far described is old and per se, forms no part of this invention, and any form of sash holder or lock may be substituted therefor or in some cases it may be desirable to omit the sash holding feature.

40 14 is the sash starter member movable downwardly against an abutment 16 which is here shown as provided on the sill 15. It will be understood that the sill has two top surfaces at different levels and that the sash when closed, bottoms on the lower level. The abutment when on the sill is on the upper level.

45 55 The sash starter is here shown arranged in the path of the lever 8 to be actuated thereby and as pivotally connected to the lever 8, and as movable endwise downwardly through an opening 17 in the lower wall of the base or casing 1, and means is provided for shifting it laterally out of effective thrusting position or out of alinement with the abutment 16 when the sash holding mechanism is operated to wholly withdraw the bolt 4 or the teeth 5 thereof out of en-

gagement with the rack 6, that is, when the handle 12 of the lever 8 is closed to the pinch handle 13. Normally, the sash holding lever 14 thrusts against the abutment 16. The abutment is formed with a passage at 70 one side thereof and this passage is most conveniently provided by having the abutment raised above the upper face of the top level of the sill but it need not necessarily be so as it is only necessary that it be so arranged that the lower end of the sash starter member 14 can move past it downwardly and ratchet over it upwardly regardless of whether or not the abutment is on the sill or some other part of the window frame. The abutment is here shown as the head of a screw.

75 In the illustrated embodiment of my invention, the sash starter member 14 is a plunger pivoted at 18 to the lever 8 and depending therefrom through the hole 17, this hole slidably fitting the portion of the starter therein when the parts are in their normal position, that is, when the bolt 4 is engaged with the rack 6.

80 The means for shifting the starter laterally out of alinement with the abutment 16 at the end of the operation of the lever 12, that is, after the bolt 4 is withdrawn from the rack 6, comprises cam means including portions carried respectively by the base or casing 1, and by the member 14 and normally spaced apart and arranged to come into action when the lever 12 approaches the end of its downward movement. As here illustrated, the case 1 is provided with a cam surface 19 adjacent the opening 17 and the member 14 is formed with a projection 20 at one side of its pivot 18 and arranged to engage the cam surface 19 as the lever 12 approaches the end of its throw, and during such engagement the projection 20 slides along the cam surface 19 and forces the starter member 14 laterally out of effective thrusting position or out of alinement with the abutment 16. When the operator re-

forming the inner end portion of the starter member of less diameter than the lower portion or by cutting out the upper portion of the starter member, the projection 20 is formed at the upper end of said portion or the upper end of the cut-out and also a cam surface or part 200 is provided at the lower end of said portion or cut-out, the surface or part 200 acting to force the starting member from inclined position, Figure 3 to vertical position during the return of the holding mechanism to its normal position as the surface 200 engages the lower side at 201 of the wall around the hole 17 during the upward movement of the starter member and thus forces or cams it from inclined to straight position as the lower portion of greater diameter moves into the hole 17.

In order that there may be no lost motion in the sash holding mechanism, an additional spring 22 may be preferably employed, this spring acting directly on the handle 12 to return it to its normal position, but this spring 22 acts primarily to prevent rattling and takes up lost motion. Preferably, the sash starter member 14 has a reduced portion 23 at its upper end and shoulders 24 at the base of the reduced portion, the reduced portion extending between ears or lugs 25 on the lever 8 and being pivoted thereto by the pivot 18. The pivot is loose enough to permit the shoulders 24 to engage the lower ends of the lugs 25 when the lever 12 is being depressed so as to relieve the pivot of this thrust.

In Figure 2, a sash holding mechanism is shown with a slightly different arrangement of starter member and in Figure 2 the starter member 14^a is shown as square in cross section and as pivoted at 18^a to a single lug 25^a on the lever 8^a, the starter member sliding along the inner face or bottom of the recess 2^a. Also, the spring 22^a is shown as seated in a well 26 formed in the lower part of the casing. In Figures 2 and 4, the cam means corresponding to the cam means and the reduced portions 19, 20, 21 and 200 and 201 of Figures 1 and 3 are designated 19^a, 20^a, 21^a and 200^a and 201^a.

In operation, assuming that the sash is open, the operator normally engages the handles 12 and 13 of the sash lock on each side of the sash and pinches the handle 12 toward the fixed handle 13, thus withdrawing the bolt 4 and shifting the sash starter member laterally out of alinement with the abutment 6. The sash is then closed so that the lower rail of the sash abuts against or bottoms on the lower level of the sill and owing to the fact that the operator holds the handles pinched together, the sash starter member is out of alinement with the abutment 16 and passes to one side of said abutment, so that the sash can come completely down against the sash. After the operator

lets go of the handle 12, it returns to its normal position and the bolt engages the rack and the lever 12 in so returning to its normal position carries the sash starter member 14 up so that its upper end rests on or is opposite to the abutment, the surface 200 causing the starter member 14 to move back into effective relation or into alinement with the abutment during the upward movement of the starting member.

To raise the sash, the levers are again pinched together and a lifting force applied and during the withdrawal of the bolt, the sash starter member 14 presses downwardly against the abutment 16 and prys the sash off the sill, this prying action being completed before the sash starter member is out of effective thrusting relation or shifted laterally by the cam parts 19, 20 coming into coaction as the lever 12 approaches the end of its throw.

This starter member is particularly advantageous in that the sash can be completely closed instead of only nearly closed as in sash starters heretofore used, and further in that when closing the sash no force or sting is applied to the operator's fingers due to the fact that the sash starter infringes the sill or the abutment on the sill.

What I claim is:

1. A sash starter and holder comprising a base, sash holding mechanism carried by the base and including a movable operating element, a sash starter member pivotally connected to said element and movable downwardly thereby to pry against the window sill when said element is operated to withdraw the mechanism, and means for shifting the starting member laterally on its pivot at the end of the operating movement of said element, in combination with a raised abutment on the sill against which the starter member thrusts prior to its lateral movement.

2. A sash starter and holder comprising a base, sash holding mechanism carried by the base and including a movable operating element, a sash starter member pivotally connected to said element and movable downwardly thereby to pry against the window sill when said element is operated to withdraw the mechanism, means for guiding the starter member downwardly and means for shifting the starter member laterally on its pivot at the end of the operating movement of the lever, in combination with a raised abutment on the window sill against which the starter member thrusts during its downward movement and prior to its lateral movement.

3. A sash starter and holder comprising a base, sash holding mechanism carried by the base and including a spring for moving said mechanism into its holding position and a movable operating element, a sash starter

member connected to said element to be moved downwardly thereby during the withdrawing operation of the holding mechanism, an abutment on the sill with which said starter member coacts and means for shifting the starter member out of line with the abutment during the end of the operating movement of said element and means for bringing said member into alignment with the abutment when the operating element is released.

4. A sash starter and holder comprising a base, sash holding mechanism carried by the base and including a movable operating element, a sash starter member arranged to be operated by said element, the starter member extending downwardly and the base being formed with an opening slidably fitting the portion of the starting member normally located in said opening, an abutment on the sill normally in line with the lower end of the starter member and cam means including coacting parts on the starter member and on the base, said cam parts being normally spaced apart and arranged to coact to shift the starter member laterally as it approaches the end of its throw.

5. A sash starter and holder comprising a base, sash holding mechanism carried by the base and including a movable operating element, a sash starter member arranged to be operated by said elements, the starter member extending downwardly and the base being formed with an opening slidably fitting the portion of the starting member normally located in said opening, an abutment on the sill normally in line with the lower end of the starter member, and cam means including coacting parts on the starter member and on the base, said cam parts being normally spaced apart and arranged to coact to shift the starter member laterally as it approaches the end of its throw, the starter member being of less diameter adjacent the cam part thereon than the portion of said starter member normally located in the guide opening.

6. A sash starter and holder comprising a base, sash holding mechanism carried by the base and including a movable operating element, a sash starter member pivotally connected to said element and depending therefrom, the base being formed with an opening slidably fitting the portion of the starting member normally located thereon, an abutment on the sill normally in line with the lower end of the starter member and cam means including coacting parts on the starter member and on the base, said cam parts being normally spaced apart and arranged to coact to shift the starter member laterally as it approaches the end of its throw.

7. A sash starter and holder comprising a base, sash holding mechanism carried by

the base and including a movable operating element, a sash starter member pivotally connected to said element and depending therefrom, the base being formed with an opening slidably fitting the portion of the starting member normally located in the opening, an abutment on the sill normally in line with the lower end of the starter member and cam means including coacting parts on the starter member and on the base, said cam parts being normally spaced apart and arranged to coact to shift the starter member laterally as it approaches the end of its throw, the starter member being of less diameter adjacent the cam part thereon than the portion of said starter member normally located in the guide opening.

8. A sash starter and holder comprising a base, spring pressed sash holding mechanism carried by the base and including an operating lever, the base being formed with an opening in its lower side, a sash starter member extending through the opening and the portion thereof normally located in the opening slidably fitting the same, the starter member being pivoted at its upper end to the lever, cam means including parts normally spaced apart located respectively on the base adjacent said opening, and by the starter member toward the upper end thereof and operating to shift the starter member laterally about its pivot, the portion of the starter member adjacent the part of the cam means on the starter member being of less diameter than the portion normally located in said opening.

9. A sash starter and holder comprising manually operable sash holding mechanism, a pusher member movable downwardly against the window sill during the operation of said mechanism and means for shifting said sash starter member out of operative position at the end of the operation of the sash holding mechanism and for returning it into operative position as the sash holding mechanism returns to its normal position.

10. A sash starter and holder comprising a base, sash holding mechanism carried by the base and including a movable operating element, a sash starter member arranged to be operated by said element, the starter member extending downwardly and the base being formed with a guide opening slidably fitting the portion of the starting member normally located in said opening, an abutment on the sill normally in line with the lower end of the starter member and cam means including a stationary part on the base and a part on the starter member arranged to come into engagement with the stationary part on the base after said portion normally slidably fitting the guide opening has passed through the guide opening.

11. A combined sash holder and starter comprising a base, sash holding mechanism

carried by the base and including a movable element, a vertically movable sash starter member operable by the movable element to shift laterally relatively thereto, means 5 tending to shift said member laterally in one direction during the downward movement of said member by the movable element, and to shift said member in the opposite direction to its initial position as it approaches 10 the end of its upward vertical movement.

12. A combined sash holder and starter comprising a base, sash holding mechanism carried by the base and including a movable element, a vertically movable starter member pivoted to said element, and depending 15 therefrom, the pivot being arranged so that the starter partakes of the movement of the element and also moves on its pivot relatively to the movable element, the base having a 20 pair of engaging surfaces and said member having surfaces for coacting with the former surfaces respectively, one surface on the starter engaging one of the surfaces on the base during the downward movement of 25 the starter member to shift said member, the

other surface on the starter member engaging the other surface on the base during the return movement of the starter with the movable element to return the starter to a vertical position. 30

13. A combined sash holder and starter comprising a base, sash holding mechanism including a movable element pivoted to the base, a vertically movable sash starter pivoted to the said element at a point remote 35 from the former pivot whereby the starter is carried by and moves with the movable element during the pivotal movement of said element, means tending to shift the starter on its pivot during the downward movement 40 of the starter and said movable element and to shift the starter on its pivot into vertical position during the upward return movement of the movable element and the starter. 45

In testimony whereof, I have hereunto signed my name, at Syracuse, in the county of Onondaga, and in the State of New York, this 31st day of January, 1927.

EDWARD F. CHAFFEE.
